3-OXYGENATED BISNOR-17(20)-CHOLEN-22-OLS

Raymond L. Pederson and Erik H. Jensen, Kalamazoo Township, Kalamazoo County, Mich., assignors to The Upjohn Company, Kalamazoo, Mich., a corporation of Michigan

No Drawing. Application October 10, 1955
Serial No. 539,673

16 Claims. (Cl. 260—397.3)

The present invention relates to 17-ketosteroids and is more particularly concerned with 17-ketosteroids selected from the group consisting of 3-oxygenated 17-ketoandrostanes and 17-ketoetiocholanes, the intermediate 3-oxygenated bisnor-17(20)-cholen-22-ols and the 22-esters thereof, and the process of production therefor.

The novel process and the new intermediates II, bisnor-17(20)-cholen-22-ols and 22-acylates thereof, therein produced may be illustratively represented by the following equations:

wherein R is selected from the group consisting of hydrogen and acyl, the acyl group being of an organic carboxylic acid containing from one to eight carbon atoms, inclusive, and wherein R' is selected from the group consisting of hydroxy, acyloxy, the acyl group of which is defined as above, and keto. In the preferred embodiment of the invention the acyl radical is of a hydrocarbon carboxylic acid containing from one to eight carbon atoms, inclusive.

The term bisnor-17(20)cholene is used generically in the description and claims and includes those bisnor-17(20)-cholenes having additional double bonds, such as in positions 4, 5(6), and the like. These compounds are preferably, but not necessarily, oxygenated in the 3-position that is substituted by hydroxy and acyloxy, wherein the acyl group is of an organic carboxylic, preferably a hydrocarbon carboxylic acid containing from one to eight carbon atoms, inclusive, or keto group.

The term 17-ketoandrostane is used in its generic sense and refers throughout the description and claims to 17-ketoandrostanes with or without double bonds in positions 4 or 5 or in additional positions and preferably oxygenated in the 3-position, that is substituted by hydroxy and acyloxy, defined as shown above, or a keto group.

Similarly, the term 17-ketoetiocholane is used generical-

2

ly and includes 17-ketoetiocholanes which may have double bonds in positions 6(7), 9(11), or the like, and which are preferably oxygenated in position 3, having a 3-hydroxy, acyloxy, as defined above, or a keto group.

The process of the present invention comprises selectively reducing the 22-aldehyde group of a bisnor-17(20)-cholen-22-al (I) with a metal borohydride to obtain the corresponding bisnor-17(20)-cholen-22-ol and thereafter subjecting the thus obtained bisnor-17(20)-cholen-22-ol (II) or the 22-ester thereof, produced by esterification of the obtained bisnor-17(20)-cholen-22-ol, to ozonolysis to obtain the corresponding 17-ketoandrostane or 17-ketoetiocholane (III).

It is an object of the present invention to provide a method for the production of 17-ketosteroids of the androstane and etiocholane series from the corresponding 17(20)-bisnorcholene aldehydes through selective reduction of the aldehyde group to the alcohol group with or without esterification of the thus obtained 17(20)-bisnor-cholen-22-ol and selective ozonolysis of the 17(20)-double bond. It is another object of the instant invention to produce new and useful steroid intermediates belonging to the class of bisnor-17(20)-cholen-22-ols and 22-esters thereof through selective reduction of the bisnor-17(20)-cholen-22-ols in the presence of double bonds and/or keto groups and esterification of the 22-alcohol group by conventional methods. A particular object of the instant invention is the provision of a process for the production of bisnor-17(20)-cholen-22-ols such as especially the 3-ketobisnor-4,17(20)-choladien-22-ol, 3-ketobisnor-17(20)-cholen-22-ol, 3-acyloxybisnor-5,17(20)-choladien-22-ol wherein the acyl group is defined as before, bisnor-5,17(20)-choladiene-3,22-diol and the respective 6- and 11-hydroxy, acyloxy, keto derivatives thereof and the corresponding 22-organic carboxylic and preferably hydrocarbon carboxylic acids thereof. Other objects of the present invention will be apparent to those skilled in the art to which this invention pertains.

The intermediates and the process of the present invention are useful for the production of physiologically active compounds and key-intermediates for the production of such physiologically active compounds belonging to the androstane and etiocholane series. Thus through reduction of 3-ketobisnor-4,17(20)-choladien-22-al is obtained 3-ketobisnor-4,17(20)-choladien-22-ol which by ozonolysis yields 4-androstene-3,17-dione possessing androgenic properties and being an intermediate in the production of testosterone. In a similar manner 3-ketobisnor-4,17(20)-choladien-22-ol 22-acylate, such as the acetate propionates, benzoates, and the like, are useful to give by ozonolysis or chromic acid oxidation, 4-androstene-3,17-dione; 3,11-diketobisnor-4,17(20)-choladien-22-ol and 22-esters thereof, obtained by reduction of 3,11-diketobisnor-4,17(20)-choladien-22-ols are useful for the production of androgenically and anabolically active adrenosterone; 3 α - or 3 β -hydroxybisnor-17(20)-cholen-22-ol and 22-acylates thereof give anesthetically active 3 α - or 3 β -hydroxyetiocholan-17-one; 3,11-diketobisnor-17(20)-cholen-22-ol gives etiocholane-3,11,20-trione (general anesthetic activity), 3-hydroxy- or 3-acyloxy-6-ketobisnor-17(20)-cholen-22-ol provide the corresponding 3-hydroxyetiocholane-6,17-dione and 3-esters thereof which can be oxidized, after hydrolysis, in the case of a 3-ester, to the corresponding etiocholane-3,6,17-trione which may be brominated to 4-bromoetiocholane-3,6,17-trione and dehydrobrominated to give 4-androstene-3,6,17-trione of estrogenic activity. Similarly the etiocholane-3,6,17-trione from which 4-androstene-3,6,17-trione is prepared, may also be prepared by the method of the present invention from 3,6-diketobisnor-17(20)-cholen-22-ol. 3,11-

bisnorallo-17(20)-cholen-22-ol yields androgenically active androstane-3,11,17-trione by the method of the present invention.

The starting compounds of the present invention are bisnor-17(20)-cholen-22-als, such as illustratively: bisnor-17(20)-cholen-22-ol, bisnor-4,17(20)-choladien-22-ol, 3-ketobisnor-4,17(20)-choladien-22-ol, 3-hydroxybisnor-17(20)-cholen-22-ol, 3 α - and 3 β -acetoxybisnor-17(20)-cholen-22-ol, 3 α - and 3 β -hydroxybisnor-5,17(20)-choladien-22-ol, 3 α - and 3 β -acetoxybisnor-5,17(20)-choladien-22-ol, 3,11-diketobisnor-4,17(20)-choladien-22-ol, 3-ketoallo-bisnor-17(20)-cholen-22-ol, 3,11-diketoallo-bisnor-17(20)-cholen-22-ol, 3,6-diketobisnor-17(20)-cholen-22-ol, 3-ketobisnor-11 α -hydroxy- and 3-ketobisnor-11 β -hydroxy-4,17(20)-choladien-22-ol, 3 β -hydroxy- and 3 β -acetoxy-6-ketobisnor-17(20)-cholen-22-ol, 3-acetoxyallo-bisnor-17(20)-cholen-22-ol, 3,11-dihydroxybisnor-17(20)-cholen-22-ol, 3,12-dihydroxybisnor-17(20)-cholen-22-ol, 3-acyloxybisnor-17(20)-cholen-22-ol, 3-acyloxybisnor-5,17(20)-choladien-22-ol, 3-acyloxy-6-ketobisnor-17(20)-cholen-22-ol, 3-acyloxybisnor-17(20)-cholen-22-ol, 3-ketobisnor-11 α -acyloxy-4,17(20)-choladien-22-ol, 3,11-diacyloxybisnor-17(20)-cholen-22-ol, 3,12-diacyloxybisnor-17(20)-cholen-22-ol, and the like, wherein the acyloxy groups are of an organic carboxylic acid containing from one to eight carbon atoms, inclusive, preferably of a hydrocarbon carboxylic acid containing from one to eight carbon atoms, inclusive. Representative acyloxy groups illustratively comprise: formyloxy, acetoxy, propionyloxy, butyryloxy, isobutyryloxy, valeryloxy, isovaleryloxy, hexanoxyloxy, heptanoyloxy, octanoyloxy, benzyloxy, β -cyclopentylpropionyloxy, dimethylacetoxyl, trimethylacetoxyl, phenylacetoxyl, toluylloxy, anisoyloxy, gallyloxy, salicyloyloxy, cinnamylloxy, hemisuccinylloxy, hemitartraryloxy, dihydrogencitryloxy, hemimaleylloxy, hemifumarylloxy, crotonyloxy, acrylicloxy, β -methylcrotonyloxy, cyclohexane-carboxyloxy, chloroacetoxyl, dichloroacetoxyl, trichloroacetoxyl, bromoacetoxyl, hemiquinolinoyloxy, nicotinyloxy, piperonyloxy, 2-furoyloxy, thioglycolyloxy, para-chlorobenzoyloxy, para-bromobenzoyloxy, meta-nitrobenzoyloxy, 3,5-dinitrobenzoyloxy, benzenesulfonyloxy, para-chlorobenzenesulfonyloxy, para-toluenesulfonyloxy, para-nitrobenzenesulfonyloxy, 3,5-dinitrobenzenesulfonyloxy, benzenephosphonyloxy, and the like.

The preparation of the starting compounds belonging to the new class of bisnor-17(20)-cholen-22-als is described in detail in copending application Serial No. 539,671, filed October 10, 1955, and comprises: reacting a bisnorcholan aldehyde either available or produced by reduction of the carboxyl group of the known bisnorcholanic acid to an aldehyde group by methods known in the art [Rosemund, McFayden-Stevens and the more recent method by Weygand et al., Angew. Chem. 65, 525 (1953)] with a secondary amine, preferably a cyclic secondary amine such as piperidine, morpholine, pyrrolidine, homomorpholine, oxazolidine, and the like, to obtain the corresponding 22-(N-tertiaryamino)-bisnor-20(22)-cholen, brominating the thus obtained 22-(N-tertiaryamino)-bisnor-20(22)-cholene at a temperature between about minus thirty and plus twenty degrees centigrade to obtain a 20-bromobisnorcholan-22-ol and dehydrobrominating with pyridine or other tertiary amines to obtain the corresponding bisnor-17(20)-cholen-22-ol.

In carrying out the process of the present invention the selected bisnor-17(20)-cholen-22-ol, dissolved in an organic solvent, is treated with a metal borohydride. Solvents used in this reduction are aqueous solutions of dioxane, methanol, ethanol, tetrahydrofuran, isopropyl alcohol, tertiary butyl alcohol, and the like. The metal

borohydrides used are essentially the alkali-metal borohydride such as lithium, sodium or potassium borohydride. However, other metal hydrides such as calcium, zinc, cadmium, aluminum and ammonium borohydride, are operative. The reduction reaction is performed at a temperature between minus ten degrees centigrade and the boiling temperature of the solvents, up to 100 degrees centigrade, but is preferably conducted at room temperature, that is between twenty to thirty degrees centigrade. The time of reaction is between fifteen minutes and four hours preferably between one and two hours and at the end of this time the reaction is stopped by the decomposition of the metal borohydride, for example, by adding a dilute mineral acid such as hydrochloric or sulfuric acid. The amount of metal borohydride used is generally in a ratio of stoichiometric proportions of each to an excess of the borohydride ranging up to five equivalents. One fourth mole of borohydride to one mole of steroids is commonly used. Larger or smaller amounts of metal borohydride can be used but no advantages are obtained. Larger amounts of borohydride may reduce the carbonyl groups on other positions than the 22-aldehyde group. The reaction product is separated from the mixture by conventional means such as chromatography or extraction with a water-immiscible solvent, for example, ether, benzene, chloroform, carbon tetrachloride, methylene dichloride, ethylene dichloride, or the like, followed by drying and evaporating the solvent to obtain the solid reaction product. Recrystallization from convenient organic solvents such as methanol, ethanol, acetone Skellysolve B hexanes, ethyl acetate, mixtures of these, or the like, and/or chromatography are used to obtain the pure reaction product.

The ozonolysis of the reaction product, a bisnor-17(20)-cholen-22-ol, is carried out in conventional manner, by dissolving the product in a convenient solvent such as methylene chloride, chloroform, ethyl acetate, cyclohexane, or the like, and letting a stream of ozone-oxygen pass through the cooled solution. Temperatures between minus 75 degrees and plus 25 degrees centigrade are operative, with the preferred range between minus thirty and about minus seventy degrees centigrade. The solution containing the ozonide of the 17(20)-cholen-22-ol is then decomposed by the addition of acetic acid and zinc dust, in the preferred embodiment under continuous stirring. The decomposition of the ozonide by zinc and acetic acid is performed at room temperature and requires a reaction period between fifteen minutes and several hours. The reaction product is separated by conventional means such as filtering the solution to remove the zinc dust, washing and evaporating the solvent, and recrystallization or chromatography as deemed necessary to obtain a pure 17-ketosteroid.

The following examples are illustrative of the process and products of the present invention but are not to be construed as limiting.

EXAMPLE 1

3-ketobisnor-4,17(20)-choladien-22-ol

A solution containing 4.90 grams of 3-ketobisnor-4,17(20)-choladien-22-ol in a mixture of fifty milliliters of dioxane and twenty milliliters of water, was reacted with 100 milliliters of 0.5 N sodium borohydride in 1 N aqueous sodium hydroxide solution. One mole of sodium borohydride (NaBH_4) by reaction with water is capable of giving eight hydrogen equivalents; therefore a 0.5 normal sodium borohydride solution corresponds to one sixteenth molar sodium borohydride solution. After a period of ninety minutes the mixture was stopped by adding 100 milliliters of 4 N sulfuric acid. The reaction mixture was then extracted with benzene, the extract was washed with dilute alkali and thereafter with water. The benzene layer was separated from the water layer and evaporated to give 4.91 grams of residue which was chromatographed over 400 grams of Florisil with petroleum ether of boiling

range 30-60 degrees centigrade containing acetone. The following fractions of 500 milliliters each were taken:

TABLE I

Fraction	Solvent
1-24	petroleum ether-acetone 97:3
25-32	petroleum ether-acetone 96:4
33-40	petroleum ether-acetone 92:8
41-48	petroleum ether-acetone 85:15

Fractions 42 thru 48, inclusive, were combined and evaporated to yield 1.32 grams of 3-ketobisnor-4,17(20)-choladien-22-ol. The thus obtained crude 3-ketobisnor-4,17(20)-choladien-22-ol of melting point 160 to 170 degrees centigrade was recrystallized from acetone to give a pure sample of 3-ketobisnor-4,17(20)-choladien-22-ol of melting point 166 to 168 degrees centigrade, rotation $[\alpha]_D$ plus 109 degrees (in chloroform)

$\lambda_{\text{max}}^{\text{abs}}$ 242 mmu, 16,700

Analysis.—Calcd. for $C_{22}H_{32}O_2$: C, 80.44; H, 9.82. Found: C, 80.05; H, 9.94.

EXAMPLE 2

3-ketobisnor-4,17(20)-choladien-22-ol 22-acetate

A solution containing 500 milligrams of 3-ketobisnor-4,17(20)-choladien-22-ol in a mixture of eight milliliters of pyridine and four milliliters of acetic anhydride was allowed to stand at room temperature (22-25 degrees centigrade) over a period of sixteen hours. Thereafter the solution was poured into 75 milliliters of ice-water and thus-formed precipitate collected on filter. Recrystallization of the precipitate from ethyl acetate and Skellysolve B hexanes yielded pure 3-ketobisnor-4,17(20)-choladien-22-ol 22-acetate.

EXAMPLE 3

3-ketobisnor-4,17(20)-choladien-22-ol 22-benzoate

In the manner shown in Example 2, reacting 3-ketobisnor-4,17(20)-choladien-22-ol with benzoylchloride in pyridine solution results in 3-ketobisnor-4,17(20)-choladien-22-ol 22-benzoate.

EXAMPLE 4

3-ketobisnor-4,17(20)-choladien-22-ol 22-propionate

In the manner shown in Example 2, reacting 3-ketobisnor-4,17(20)-choladien-22-ol with propionic anhydride in pyridine solution results in 3-ketobisnor-4,17(20)-choladien-22-ol 22-propionate.

EXAMPLE 5

3-ketobisnor-4,17(20)-choladien-22-ol 22-valerate

In the manner shown in Example 2, reacting 3-ketobisnor-4,17(20)-choladien-22-ol with valeric anhydride in pyridine solution results in 3-ketobisnor-4,17(20)-choladien-22-ol 22-valerate.

EXAMPLE 6

3-ketobisnor-4,17(20)-choladien-22-ol 22-phenylacetate

In the manner shown in Example 2, reacting 3-ketobisnor-4,17(20)-choladien-22-ol with phenylacetyl bromide in pyridine solution results in 3-ketobisnor-4,17(20)-choladien-22-ol 22-phenylacetate.

EXAMPLE 7

3-ketobisnor-4,17(20)-choladien-22-ol 22- β -cyclopentylpropionate

In the manner shown in Example 2, reacting 3-ketobisnor-4,17(20)-choladien-22-ol with β -cyclopentylpropionyl chloride in pyridine solution results in 3-ketobisnor-4,17(20)-choladien-22-ol 22- β -cyclopentylpropionate.

In the same manner as given in Examples 2 through 7, other 3-ketobisnor-4,17(20)-choladien-22-ol 22-acylates

ates are obtained by reacting 3-ketobisnor-4,17(20)-choladien-22-ol with an acylating reagent such as an organic carboxylic acid halide or anhydride and preferably a hydrocarbon carboxylic acid halide or anhydride having from one to eight carbon atoms, inclusive. Representative 3-ketobisnor-4,17(20)-choladien-22-ol 22-acylates thus obtained comprise the 3-ketobisnor-4,17(20)-choladien-22-ol 22-butyrate, isobutyrate, isovalerate, hexanoate, heptanoate, octanoate, toluate, trimethylacetate, 2-furoate, nicotinate, cinnamate, salicylate, trichoroacetate, bromoacetate, o-, p-, m-bromobenzoate, o-, p-, m-nitrobenzoate, 3,5-dinitrobenzoate, piperonate, p-toluenesulfonate, benzene-sulfonate, methanesulfonate and the like.

EXAMPLE 8

4-androstene-3,17-dione

A solution containing 82 milligrams of 3-ketobisnor-4,17(20)-choladien-22-ol, 0.5 milliliter of pyridine, and fifty milliliters of methylene chloride was cooled in a Dry-Ice acetone bath. An ozone-oxygen stream containing 0.0275 millimole of ozone per minute of flow (in 200 milliliters of oxygen) was added for a period of 13.6 minutes. The reaction mass was thereupon poured onto 0.5 gram of zinc dust and stirring started; twenty milliliters of acetic acid was added and stirring continued for a period of two hours. The reaction mixture was then filtered, washed with water and the solvent was evaporated to leave 79 milligrams of a white solid. The thus obtained crude 4-androstene-3,17-dione was chromatographed over Florisil taking the following fifty-milliliter fractions:

TABLE II

Fraction	Solvent
35	
1-5	Skellysolve B-acetone 96:4.
6-15	Skellysolve B-acetone 95:5.

Fractions 7 to 11 were combined and recrystallized from methylene chloride Skellysolve B hexanes giving pure 4-androstene-3,17-dione of melting point 175 to 176 degrees centigrade. Infrared spectrum was compared to that of a known sample and found to be identical.

Analysis.—Calcd. for $C_{19}H_{28}O_2$: C, 79.68; H, 9.15. Found: C, 79.36; H, 9.12.

EXAMPLE 9

4-androstene-3,17-dione from 3-ketobisnor-4,17(20)-choladien-22-ol 22-acetate

A solution containing 100 milligrams of 3-ketobisnor-4,17(20)-choladien-22-ol 22-acetate, 0.5 milliliter of pyridine and fifty milliliters of methylene chloride was cooled in a Dry-Ice acetone bath. An ozone-oxygen stream containing 0.0275 millimole of ozone per minute of flow was added over a period of twelve minutes. The reaction mass was thereupon poured onto 0.5 gram of zinc dust. Thereto was added under continuous stirring twenty milliliters of acetic acid. The reaction mixture was filtered, washed with water, dried over anhydrous sodium sulfate, and the solvent was evaporated to give as a white crystalline solid crude 4-androstene-3,17-dione, which is purified in the manner shown in Example 8.

In the same manner as given in Example 9, other 3-ketobisnor-4,17(20)-choladien-22-ol 22-acylates such as shown in Examples 3 through 7, inclusive, can be ozonolized to give 4-androstene-3,17-dione. Alternatively 3-ketobisnor-4,17(20)-choladien-22-ol 22-acylates can be converted to 4-androstene-3,17-dione through oxidation with chromic anhydride in acetic acid solution at temperatures between zero and fifty degrees centigrade.

EXAMPLE 10

3 α -acetoxybisnor-4,17(20)-cholen-22-ol

Otherwise like Example 1, 3 α -acetoxybisnor-4,17(20)-cholen-22-ol, dissolved in ethanol, was treated with

potassium borohydride in the presence of an aqueous solution of potassium hydroxide. The mixture thereafter was extracted with chloroform, the chloroform solution was dried over anhydrous sodium sulfate and evaporated to give white crystals which were purified by recrystallization from ethyl acetate-Skellysolve B hexanes to give pure 3α -acetoxybisnor-17(20)-cholen-22-ol.

In the same manner as given in Example 2, 22-acylates of 3α -acetoxybisnor-17(20)-cholen-22-ol, such as $3\alpha,22$ -diacetoxybisnor-17(20)-cholen may be prepared.

EXAMPLE 11

3α -acetoxyetiocholen-17-one

In the manner given in Example 2, 3α -acetoxybisnor-17(20)-cholen-22-ol was subjected to ozonolysis while dissolved in methylene dichloride to give 3α -acetoxyetiocholan-17-one.

In the same manner as shown in Example 9, 22-acylates of 3α -acetoxybisnor-17(20)-cholen-22-ol, illustratively $3\alpha,22$ -diacetoxybisnor-17(20)-cholen is converted to 3α -acetoxyetiocholen-17-one thru ozonolysis.

EXAMPLE 12

$3,11$ -diketobisnor-4,17(20)-choladien-22-ol

In the manner given in Example 1, $3,11$ -diketobisnor-4,17(20)-choladien-22-al, dissolved in tetrahydrofuran, was reacted with lithium borohydride in the presence of an aqueous solution of sodium hydroxide. The thus obtained reaction mixture was extracted with benzene, the benzene layer washed repeatedly with water, dried over anhydrous sodium sulfate and evaporated to give $3,11$ -diketo-4,17(20)-choladien-22-ol.

In the same manner as given in Example 2, treating $3,11$ -diketobisnor-4,17(20)-choladien-22-ol with propionic anhydride is productive of the $3,11$ -diketobisnor-4,17(20)-choladien-22-ol 22-propionate. In the same manner as given in Examples 3 thru 7, other 22-acylates of $3,11$ -diketobisnor-4,17(20)-choladien-22-ol are obtained.

EXAMPLE 13

4 -androstene-3,11,17-trione (adrenosterone)

Ozonolyzing (i. e. ozonizing and decomposing the ozonide) in the manner shown in Example 2, $3,11$ -diketobisnor-4,17(20)-choladien-22-ol produced 4 -androstene-3,11,17-trione (adrenosterone).

In the same manner as shown in Example 9, 22-acylates of $3,11$ -diketobisnor-4,17(20)-choladien-22-ol when subjected to ozonolysis give adrenosterone.

EXAMPLE 14

3β -acetoxy-6-ketobisnor-17(20)-cholen-22-ol

In the manner given in Example 1, reacting 3β -acetoxy-6-ketobisnor-17(20)-cholen-22-al, dissolved in dioxane and water, with sodium borohydride, dissolved in one Normal sodium hydroxide solution, yielded the 3β -acetoxy-6-ketobisnor-17(20)-cholen-22-ol.

EXAMPLE 15

3β -acetoxyetiocholane-6,17-dione

Ozonolyzing in the manner shown in Example 2, 3β -acetoxy-6-ketobisnor-17,20-cholen-22-ol produced 3β -acetoxyetiocholane-6,17-dione. Hydrolysis of 3β -acetoxyetiocholane-6,17-dione with sodium hydroxide produced 3β -hydroxyetiocholane-6,17-dione.

EXAMPLE 16

$3,6$ -diketobisnor-17(20)-cholen-22-ol

In the manner given in Example 1, reacting $3,6$ -diketobisnor-17(20)-cholen-22-al, dissolved in dioxane and water, with sodium borohydride, dissolved in one Normal sodium hydroxide solution, yielded the $3,6$ -diketobisnor-17(20)-cholen-22-ol.

EXAMPLE 17

Etiocholane-3,6,17-trione

Ozonolyzing in the manner shown in Example 2, $3,6$ -diketobisnor-17(20)-cholen-22-ol produced etiocholane-3,6,17-trione.

EXAMPLE 18

3 -ketobisnorallo-17(20)-cholen-22-ol

In the manner given in Example 1, reacting 3 -ketobisnorallo-17(20)-cholen-22-al, dissolved in dioxane and water, with sodium borohydride dissolved in one Normal sodium hydroxide solution, yielded the 3 -ketobisnorallo-17(20)-cholen-22-ol.

EXAMPLE 19

Androstane-3,17-dione

Ozonolyzing in the manner shown in Example 2, 3 -ketoallobisnor-17(20)-cholen-22-ol produced androstane-3,17-dione.

EXAMPLE 20

3α -hydroxybisnor-5,17(20)-choladien-22-ol

In the manner given in Example 1, reacting 3α -hydroxybisnor-5,17(20)-choladien-22-al, dissolved in dioxane and water, with potassium borohydride, dissolved in one Normal potassium hydroxide solution, yielded the 3α -hydroxybisnor-5,17(20)-choladien-22-ol.

EXAMPLE 21

3α -hydroxy-5-androsten-17-one

Ozonolyzing in the manner shown in Example 2, 3α -hydroxybisnor-5,17(20)-choladien-22-ol produced 3α -hydroxy-5-androsten-17-one.

EXAMPLE 22

3α -hydroxyallobisnor-17(20)-cholen-22-ol

In the manner given in Example 1, reacting 3α -hydroxyallobisnor-17(20)-cholen-22-al, dissolved in dioxane and water, with sodium borohydride, dissolved in one Normal sodium hydroxide solution, yielded the 3α -hydroxyallobisnor-17(20)-cholen-22-ol.

EXAMPLE 23

3α -hydroxyandrostan-17-one

Ozonolyzing in the manner shown in Example 2, 3α -hydroxyallobisnor-17(20)-cholen-22-ol produced 3α -hydroxyandrostan-17-one.

EXAMPLE 24

3α -acetoxyallobisnor-17(20)-cholen-22-ol

In the manner given in Example 1, reacting 3α -acetoxyallobisnor-17(20)-cholen-22-al, dissolved in dioxane and water, with sodium borohydride, dissolved in one Normal sodium hydroxide solution, yielded the 3α -acetoxyallobisnor-17(20)-cholen-22-ol.

EXAMPLE 25

3α -acetoxyandrostan-17-one

Ozonolyzing in the manner shown in Example 2, 3α -acetoxyallobisnor-17(20)-cholen-22-ol produced 3α -acetoxyandrostan-17-one.

EXAMPLE 26

$3,11$ -diketobisnor-17(20)-cholen-22-ol

In the manner given in Example 1, reacting $3,11$ -diketobisnor-17(20)-cholen-22-al, dissolved in dioxane and water, with sodium borohydride dissolved in one Normal sodium hydroxide solution, yielded the $3,11$ -diketobisnor-17(20)-cholen-22-ol.

EXAMPLE 27

Etiocolane-3,11,17-trione

Ozonolyzing in the manner shown in Example 2, 3,11-diketobisnor-17(20)-cholen-22-ol produced etiocolane-3,11,17-trione.

EXAMPLE 28

3-ketobisnor-17(20)-cholen-11 α ,22-diol

In the manner given in Example 1, reacting 3-ketobisnor-11 α -hydroxy-17(20)-cholen-22-ol, dissolved in dioxane and water, with sodium borohydride, dissolved in one Normal sodium hydroxide solution, yielded the 3-ketobisnor-17(20)-cholen-11 α ,22-diol.

EXAMPLE 29

11 α -hydroxyeticholane-3,17-dione

Ozonolyzing in the manner shown in Example 2, 3-ketobisnor-17(20)-cholen-11 α ,22-diol produced 11 α -hydroxyeticholane-3,17-dione.

EXAMPLE 30

3-ketobisnor-17(20)-cholen-11 β ,22-diol

In the manner given in Example 1, reacting 3-ketobisnor-11 β -hydroxy-17(20)-cholen-22-ol, dissolved in dioxane and water, with sodium borohydride, dissolved in one Normal sodium hydroxide solution, yielded the 3-ketobisnor-17(20)-cholen-11 β ,22-diol.

EXAMPLE 31

11 β -hydroxyeticholane-3,17-dione

Ozonolyzing in the manner shown in Example 2, 3-ketobisnor-17(20)-cholen-11 β ,22-diol produced 11 β -hydroxyeticholane-3,17-dione.

EXAMPLE 32

3,11-diketobisnorallo-17(20)-cholen-22-ol

In the manner given in Example 1, reacting 3,11-diketobisnorallo-17(20)-cholen-22-ol, dissolved in dioxane and water, with sodium borohydride, dissolved in aqueous one Normal sodium hydroxide solution, yielded the 3,11-diketobisnorallo-17(20)-cholen-22-ol.

EXAMPLE 33

Androstan-3,11,17-trione

Ozonolyzing in the manner shown in Example 2, 3,11-diketobisnorallo-17(20)-cholen-22-ol produced androstan-3,11,17-trione.

EXAMPLE 34

Bisnor-17(20)-cholen-3 α ,22-diol

In the manner given in Example 1, reacting 3 α -hydroxybisnor-17(20)-cholen-22-ol, dissolved in dioxane and water, with sodium borohydride, dissolved in one Normal sodium hydroxide solution, yielded the bisnor-17(20)-cholen-3 α ,22-diol.

EXAMPLE 35

3 α -hydroxyetiocholan-17-one

Ozonolyzing in the manner shown in Example 2, bisnor-17(20)-cholen-3 α ,22-diol produced 3 α -hydroxyetiocholan-17-one.

EXAMPLE 36

Bisnor-5,7,17(20)-cholatrien-3 β ,22-diol 5,8-maleic anhydride adduct

In the manner given in Example 1, reacting 3 β -hydroxybisnor-5,7,17(20)-cholatrien-22-ol 5,8-maleic anhydride adduct, dissolved in dioxane and water, with sodium borohydride, dissolved in one Normal sodium hydroxide solution, yielded the bisnor-5,7,17(20)-cholatrien-3 β ,22-diol 5,8-maleic anhydride adduct.

EXAMPLE 37

3 β -hydroxy-5,7-androstadien-17-one 5,8-maleic acid anhydride adduct

Ozonolyzing in the manner shown in Example 2, bisnor-5,7,17(20)-cholatrien-3 β ,22-diol 5,8-maleic anhydride adduct produced 3 β -hydroxy 5,7-androstadien-17-one 5,8-maleic acid anhydride adduct.

In the same manner as Example 1, other bisnor-17(20)-cholen-22-ols may be produced by reducing the corresponding bisnor-17(20)-cholen-22-ol, dissolved in a suitable organic solvent in the presence of water, with sodium, potassium or lithium borohydride. Representative bisnor-17(20)-cholen-22-ols thus obtained comprise: 3-ketobisnor-11 α -hydroxy-4,17(20)-choladien-22-ol, 3-ketobisnor-6 β ,11 α -dihydroxy-4,17(20)-choladien-22-ol, 3,6-diketobisnor-11 α -acetoxy-4,17(20)-choladien-22-ol, 3-ketobisnor-6 β ,11 α -dipropionyloxy-4,17(20)-choladien-22-ol, 3,12-diketobisnor-4,17(20)-choladien-22-ol, 3,7-diketobisnor-17(20)-cholen-22-ol, and the like.

These bisnor-17(20)-cholen-22-ols can be subjected to ozonolysis in the manner shown in Example 2 to give respectively 11 α -hydroxy-4-androstene-3,17-dione, 6 β ,11 α -dihydroxy-4-androstene-3,17-dione, 11 α -acetoxyandrostane-3,17-dione, 6 β ,11 α -dipropionyloxy-4-androstene-3,17-dione, 4-androstene-3,12,17-trione, androstane-3,7,17-trione, and the like.

In the same manner as shown in Examples 2 through 7, inclusive, 22-acylates of the obtained bisnor-17(20)-cholen-22-ols can be produced by esterification of these 22-alcohols in conventional manner such as, for example, with acid halides and anhydrides. 22-acylates thus produced include the 22-acetates, benzoates, phenylacetates, phenylpropionates, toluates, propionates, butyrates, valerates, hexanoates, heptanoates, and the like, of 3,6-diketobisnor-17(20)-cholen-22-ol, 3 α -hydroxybisnor-5,17(20)-choladien-22-ol, 3 α -hydroxyallobisnor-17(20)-cholen-22-ol, 3 α -acetoxyallobisnor-17(20)-cholen-22-ol, 3,11-diketobisnor-17(20)-cholen-22-ol, 3-ketobisnor-17(20)-cholen-11 α ,22-diol, 3,11-diketobisnor-17(20)-cholen-3 α ,22-diol, 3-ketobisnor-6 β ,11 α -dihydroxy-4,17(20)-choladien-22-ol, 3,6-diketobisnor-11 α -acetoxy-4,17(20)-cholen-22-ol, and the like.

These compounds by oxidation with chromic acid or by ozonolysis as described previously split off the 17(20)-side chain, attached by a double bond, and give the corresponding 17-ketoandrostanes, respectively 17-ketoetiocholane compound.

It is to be understood that the invention is not to be limited to the exact details of operation or exact compounds shown and described, as obvious modifications and equivalents will be apparent to one skilled in the art, and the invention is therefore to be limited only by the scope of the appended claims.

We claim:

1. A compound selected from the group consisting of 3-oxygenated bisnor-17(20)-cholen-22-ol and 3-oxygenated bisnor-17(20)-cholen-22-ol 22-acylates and the corresponding nuclearly unsaturated compounds having a double bond at a position of the nucleus selected from 4(5) and 5(6), wherein the acyl group is that of a hydrocarbon carboxylic acid containing from one to eight carbon atoms, inclusive, and wherein the 3-oxygenated group is selected from the class consisting of keto, hydroxy and acyloxy, wherein the acyl group is defined as above.
2. 3-ketobisnor-4,17(20)-choladien-22-ol.
3. 3-ketobisnor-4,17(20)-choladien-22-ol 22-acetate.
4. 3,11-diketobisnor-4,17(20)-choladien-22-ol.
5. 3-ketobisnorallo-17(20)-cholen-22-ol.

6. 3α -acetoxybisnor-17(20)-cholen-22-ol.

7. A process for the production of a 3-oxygenated bisnor-17(20)-cholen-22-ol, which comprises: reacting a 3-oxygenated bisnor-17(20)-cholen-22-al wherein the 3-oxygenated group is selected from the class consisting of hydroxy, acyloxy, wherein the acyl radical is of an organic carboxylic acid, containing from one to eight carbon atoms, and keto, with a metal borohydride to reduce the 22-aldehyde group and to obtain the corresponding 3-oxygenated bisnor-17(20)-cholen-22-ol.

8. A process for the production of a 3-ketobisnor-17(20)-cholen-22-ol which comprises: reacting a 3-ketobisnor-17(20)-cholen-22-al in an organic solvent containing water with a metal borohydride, dissolved in an aqueous solution of alkali metal hydroxide, to obtain the corresponding 3-ketobisnor-17(20)-cholen-22-ol.

9. A process for the production of 3-ketobisnor-4,17(20)-choladien-22-ol which comprises: reacting at a temperature between about minus ten and about plus 100 degrees centigrade 3-ketobisnor-4,17(20)-choladien-22-al, dissolved in a mixture of an organic solvent and water, with a solution of sodium borohydride and sodium hydroxide to obtain 3-ketobisnor-4,17(20)-choladien-22-ol.

10. A process for the production of 3,11-diketobisnor-4,17(20)-choladien-22-ol which comprises: reacting at a temperature between about minus ten and about plus 100 degrees centigrade 3,11-diketobisnor-4,17(20)-choladien-22-al, dissolved in a mixture of an organic solvent and water, with a solution of sodium borohydride and sodium hydroxide to obtain 3,11-diketobisnor-4,17(20)-choladien-22-ol.

11. A process for the production of 3-ketobisnorallo-17(20)-cholen-22-ol which comprises: reacting at a temperature between about minus ten and about plus 100 degrees centigrade 3-ketobisnorallo-17(20)-cholen-22-al, dissolved in a mixture of an organic solvent and water, with a solution of sodium borohydride and sodium hydroxide to obtain 3-ketobisnorallo-17(20)-cholen-22-ol.

12. A process for the production of 3α -acetoxy-bisnor-17(20)-cholen-22-ol which comprises: reacting at a temperature between about minus ten and about plus 100 degrees centigrade 3α -acetoxy-bisnor-17(20)-cholen-22-al, dissolved in a mixture of an organic solvent and water, with a solution of sodium borohydride and sodium hydroxide to obtain 3α -acetoxy-bisnor-17(20)-cholen-22-ol.

13. A process for the production of a 17-ketosteroid selected from the group consisting of 3-oxygenated 17-ketoandrostanes and 17-ketoetiocholanes which comprises: reacting a 3-oxygenated bisnor-17(20)-cholen-22-al wherein the 3-oxygenated group is selected from the

class consisting of hydroxy, acyloxy, wherein the acyl radical is of an organic carboxylic acid, containing from one to eight carbon atoms, and keto with a metal borohydride to reduce the 22-aldehyde group and to obtain the corresponding 3-oxygenated bisnor-17(20)-cholen-22-ol and subjecting the thus obtained 3-oxygenated bisnor-17(20)-cholen-22-ol to ozonolysis to obtain the corresponding 3-oxygenated 17-ketosteroid.

14. A process for the production of a 17-ketosteroid selected from the group consisting of 3-oxygenated 17-ketoandrostanes and 17-ketoetiocholanes which comprises: reacting a 3-oxygenated bisnor-17(20)-cholen-22-al wherein the 3-oxygenated group is selected from the class consisting of hydroxy, acyloxy, wherein the acyl radical is of an organic carboxylic acid, containing from one to eight carbon atoms, and keto, dissolved in an aqueous organic solvent, with a metal borohydride, dissolved in an aqueous solution of alkali metal hydroxide, to obtain the corresponding 3-oxygenated bisnor-17(20)-cholen-22-ol, 20 esterifying the thus obtained 3-oxygenated-17(20)-cholen-22-ol with an acylating agent selected from halides and anhydrides of an organic carboxylic acid containing from one to eight carbon atoms, inclusive, and subjecting the thus obtained 3-oxygenated bisnor-17(20)-cholen-22-ol 25 22-acylate to ozonolysis to obtain the corresponding 3-oxygenated 17-ketosteroid.

15. A process for the production of 4-androstene-3,17-dione which comprises: reacting at a temperature between about minus ten and about plus 100 degrees centigrade, 30 3-ketobisnor-4,17(20)-choladien-22-al, dissolved in a mixture of an organic solvent and water, with a solution of sodium borohydride and sodium hydroxide to obtain 3-ketobisnor-4,17(20)-choladien-22-ol and subjecting the thus obtained 3-ketobisnor-4,17(20)-choladien-22-ol to 35 ozonolysis to obtain 4-androstene-3,17-dione.

16. A process for the production of adrenosterone which comprises: reacting at a temperature between about minus ten and about plus 100 degrees centigrade, 3,11-diketobisnor-4,17(20)-choladien-22-al, dissolved in a mixture of an organic solvent and water, with a solution of borohydride and sodium hydroxide to obtain 3,11-diketobisnor-4,17(20)-choladien-22-ol and subjecting the thus obtained 3,11-diketobisnor-4,17(20)-choladien-22-ol to 40 ozonolysis to obtain adrenosterone.

UNITED STATES PATENT OFFICE
CERTIFICATE OF CORRECTION

Patent No. 2,844,601

July 22, 1958

Raymond L. Pederson et al.

It is hereby certified that error appears in the printed specification of the above numbered patent requiring correction and that the said Letters Patent should read as corrected below.

Column 6, line 74, for "-7(20)-" read -- -17(20)- --; column 7, line 25, for "3-11-" read -- 3,11- --; line 32, for "-4,-17(20)-" read -- -4,17(20)- --; column 8, line 12, for "-ketiobisnorallo-" read -- -ketobisnorallo- --; line 41, for "-22-ol," read -- -22-al, --; column 9, line 9, for "-ketiobisnor-" in italics, read -- -ketobisnor- -- in italics; lines 16 and 31, for "-hydroxyetiocholane-" in italics, each occurrence, read -- -hydroxyetiocholane- -- in italics; same column 9, lines 19 and 20, for "-hydroxyetiocholane-" read -- -hydroxyetiocholane- --; column 10, line 10, for "be reducing" read -- by reducing --; line 21, for "-2-ol," read -- -22-ol, --.

Signed and sealed this 12th day of May 1959.
